MILTON ABBOTT McKEE, OF NEW YORK, N. Y., ASSIGNOR TO C. B. COTTRELL & SONS COMPANY, OF NEW YORK, N. Y., AND STONINGTON, CONNECTICUT, A CORPORATION OF NEW JERSEY.

PRINTING-PLATE AND PROCESS OF PREPARING THE SAME.

No. 857,581.

Specification of Letters Patent.

Patented June 18, 1907.

Application filed December 21, 1901. Serial No. 86,786.

To all whom it may concern:

Be it known that I, MILTON ABBOTT McKEE, a citizen of the United States, and a resident of the borough of Manhattan, in the city and State of New York, have invented a new and useful Improvement in Printing-Plates and Processes of Preparing the Same, of which the following is a specification.

In the manufacture of printing plates, it is not possible to produce a plate with a perfect face or even with a face so nearly perfect as that the printers may work directly therefrom, and in consequence it is the universal practice, when printing is to be done from such plates, to resort to certain manipulations of the plate and the press, technically known as "making ready", and which consists in "underlaying" the plate and "overlaying" on the impression cylinder, so as to compensate for the irregularities of the plate and obtain therefrom impressions of the exact character required, it being usually the case that some portions of the plate should print lighter or heavier than other portions, and such variations or depths of impression may be obtained by the usual custom of "underlaying" and "overlaying". But this work is exceedingly slow, time-consuming, and in the case of artistic printing requires great skill and the employment of high priced labor.

The main object of my invention is to dispense entirely with the work of "making ready" or of "underlaying" and "overlaying" and to make the necessary corrections (or cure the defects) in the plates themselves, and so, that after treatment of the plates they may be placed on the press and the printing directly proceeded with.

In describing my invention I will refer to the treatment of an electrotype plate as this form of plate is most used in printing, but it is to be understood that my invention is broadly applicable to printing plates generally.

In carrying out my invention I take a relief plate as it comes from the electrotyper and subject it to a course of treatment whereby when the plate is finished not only will all of the original defects in the plate have been corrected, but the printing face of the plate will have been worked or brought into a con-

dition such that the exact character of impression desired from such plate may be obtained at once, for example, all those portions of the plate which are to yield heavy impressions and all those portions which are to yield lighter impressions are so treated locally as that when the plate is put upon the press it will produce impressions exactly in accordance with those predetermined by the previous treatment of the plate, all of the work being put into the plate instead of into "underlaying" and "overlaying". First a proof is taken while the plate is in the condition in which it arrives from the electrotyper, for the purpose of ascertaining the defects in the plate and determining the corrections which must be made therein and also for determining the particular portions of the plate which should be made to print respectively light and heavy. In determining these matters the proof sheet is marked in pencil where the corrections and changes in the plate are to be made, and then the pressman will cut out from the proof sheet such portions of the impression as are to be printed heavier and add to the proof sheet pieces of paper at those portions of the impression which are to print lighter, the strength of the impression being graduated or reduced to the minimum or vanishing point if desired, by adding several thicknesses of paper where needed, the rule to be observed being to build up highest where the impressions are to be lightest and to depress or cut away from the proof or base sheet where the impressions are to be heaviest, the intermediate portions to have varying thicknesses or to be built up at different levels between the two extremes where there are portions to be printed with graduated strength of impression. This proof sheet thus cut out and built up constitutes what I designate as a "matrix" and is used subsequently for the purpose of producing in the face of the plate a series of depressions and elevations the reverse of those produced in the matrix, and so that when impressions are taken from the plate the high or elevated portions of the face will yield the darkest impressions and the lower or depressed portions of the plate the lighter impressions.

Having prepared the matrix ~~so as to pre-~~

determine just what changes shall be made in the face of the plate, the matrix is then preferably laid face up on the flat, cold bed of an ordinary shaving machine and the plate 5 placed thereupon face down so that the high and low portions of the matrix shall register with those portions of the face of the plate that are to be made respectively low and elevated. The plate and the matrix being then 10 properly held in position upon the bed, the shaving knife is actuated so as to take a plurality of cuts from the back of the plate. In making these cuts the knife will cause the plate to yield or to be deflected in accordance 15 with the steps, depressions or cut-outs in the matrix, and in such a manner, as will be hereinafter more fully described, as that at the completion of the shaving operations there will be produced in the back of the plate a 20 series of depressions and elevations the opposite of those previously formed or produced in the matrix, while at the same time, owing to the resiliency of the plate, the face of the plate will be or remain straight and even or 25 substantially so. These depressions and elevations thus produced in the back of the plate are provided in order that similar depressions and elevations may subsequently be produced in the face of the plate. The 30 next preferred step in the mode of treatment of the plate is to subject the plate, while still in register with the matrix, to the action of heat and pressure, so as to enable the projections on the back of the plate to be forced 35 forward as it were, and similar projections forced into the hollows or depressions in the matrix at the face of the plate, and during this operation, inasmuch as a flat platen is employed to press upon the back of the plate 40 while the matrix and the plate lie on the bed of the machine, the back of the plate will simultaneously be pressed true or even. This operation of producing the depressions and elevations in the face of the plate and at the same time truing the back of the plate may 45 be performed in any suitable press and the bed and platen thereof may both be heated. I prefer to use heat at a temperature less than the melting point of the backing lead or 50 metal of the plate, but sufficient, however, to enable the face of the plate to conform to the face of the matrix and to retain this conformation afterward. The plate and the matrix 55 may be left together under this heat and pressure for a minute, more or less, according to the exigencies of the case.

For the purpose of expediting the finishing of the plate and insuring the setting of the face thereof to conform to the outlines of the matrix, the plate and matrix are removed from the heating and pressing machine and then placed in another press where there is no heat, and which in fact may be kept cool by the circulation of cold water 60 through the bed of the press. The plate and

the matrix may be left in the last mentioned press a couple of minutes, more or less, until the plate has sufficiently cooled and set and so that it may be handled readily without danger of changing or disturbing its form. Immediately thereafter the plate may be put upon the bed or plate-cylinder of a printing press and impressions taken therefrom without resorting to the work of "making ready" as before explained, inasmuch as it will be 70 found that the printing face of the plate will then be provided or formed with the desired depressions and elevations, which were predetermined by the pressman in the making of the matrix from the proof sheet, and which 80 in consequence, will then yield impressions light and dark of exactly the character required.

In preparing plates for fine or artistic plate printing, known as "half-tone" work to 85 which my invention is especially directed, it may sometimes be necessary or desirable to employ in connection with the hot pressing operation a sheet of blotting paper or other soft material, so as to protect the face 90 of the plate against injury, which might otherwise occur if the face were pressed directly against the paper of the matrix or the bed of the machine where the matrix is cut out.

My invention therefore consists in certain processes or improvements in the art of treating previously made relief printing plates as well as in the plate itself as a new article of manufacture, all as will be hereinafter more 100 fully described and particularly pointed out in the appended claims.

A simple illustration of this process is furnished in the accompanying drawings in which

Figure 1 represents an impression from the plate to be treated taken on the sheet of thin hard finished paper which is to form the base sheet of the matrix; Fig. 2 is a face view of said sheet with an outline of the impression showing its different parts cut out and built up as required to form the matrix; Fig. 3 is a transverse section of the matrix face upward in the line 3, 3, of Fig. 2, with the plate ready to be placed upon it face downward; Fig. 4 is a transverse sectional view of the matrix and superposed plate upon the bed of the shaving machine, illustrating the simultaneous pressing and shaving action of the knife of said machine; Fig. 5 is a transverse section of the plate face downward after the shaving operation; Fig. 6 is a transverse sectional view of the board, the matrix, the soft paper sheet and the plate as placed together to be subject to pressure and heat; Fig. 7 is a sectional view of the same parts shown in Fig. 6 after having been subjected to heat and pressure; Fig. 8 is a section of the finished plate face up. Fig. 9 is a transverse section of a flat finished printing plate em- 130

bodying my invention, and Fig. 10 is a similar view of a curved plate embodying my invention.

Similar letters of reference designate corresponding parts in all the figures.

In these views the thicknesses of the paper employed in the process and the scarcely visible greater or less prominence of parts of the surface of the plate are somewhat exaggerated to render them distinguishable to the eye.

Referring first to Fig. 1, those parts designated by the letters A require to be darker and those designated by B B' require to be made lighter. Referring next to Fig. 2, the parts A to be made darker including the greater portion of the dress are cut out from the base sheet C, as indicated on the dotted lines a a, and the parts B B' including the edges which are to be vignetted and the front and one cuff of the dress which are to be made lighter, are built up by the superposition upon them of the additional thicknesses of paper b' b² b³ b⁴. In the building up of the parts B only one thickness b' of paper is indicated, but for the building up of the parts B' to be vignetted three thicknesses b² b³ b⁴ are superposed one upon another, the said thicknesses being of such form and size that the lower one b² covers a greater portion of the base sheet C, and that b³ and b⁴ cover lesser and lesser portions and hence that the thickness of the superposition is greatest toward the outer portion of the base sheet where the impression is to be most lightened. By comparing the sectional views, Figs. 3 and 4 with the face view Fig. 2, with reference to the corresponding letters thereon, it will be understood how the matrix is formed upon and in the base sheet C, for the reception of the plate P to be treated.

In Fig. 4, D designates the shaving knife, E the bed of the shaving machine, and H shavings being removed by the knife. In Fig. 5 it will be seen how the face of the shaved plate after having been released from pressure, resumes its level form, leaving the thicker portions of the plate projecting from the back thereof. In Figs. 6 and 7, F designates the press board upon which the matrix C a b' b² b³ b⁴ is placed, and G the blotting paper between the matrix and the plate. Fig. 8 shows the finished plate having its back P even or level and having the different parts of its face P' more or less prominent according to the heaviness or lightness of imprint they are required to produce.

It will be observed that in preparing the matrix according to the preferred plan, the base sheet is cut out at those portions of the proof impression which in the final printing operation from the plate are to print darkest or heaviest; then upon the remaining portions of the base sheet are superimposed and pasted one or more plies or thicknesses of

paper or other material at those portions which are to print lighter from the plate, the built-up portions being graduated or comprising different thicknesses of material arranged in step-like order so as to reduce or 70 lighten the impression at the various desired portions of the plate, those portions of the latter which are to yield the lightest or faintest impressions having the greater number of thicknesses or built-up portions, and those 75 which are to yield heavier impressions having a lesser number of thicknesses or plies and gradually tapering or stepping down to the openings or cut-outs in the base sheet which yield the heaviest or darkest impressions. 80

Referring to Fig. 2, it will be seen that there are three pieces or portions of sheets superimposed at different places upon the base sheet, and that these portions are of 85 irregular shape and underlie one another so as to provide a series of step-like or gradually ascending series of superposed portions; that is to say, the undermost portion or mount b² projects inward toward the center 90 of the base sheet farther than the portion b³, and the latter projects inward farther than the portion b⁴, so that the combined thickness of the matrix at b² consists of the base sheet and the portion b², while the total 95 thickness of the matrix at b³ consists of the thickness of the base sheet and the thicknesses of the superposed portions b² and b³, while the thickness of the matrix at b⁴ consists of the thicknesses of the base sheet and 100 the superposed portions b², b³, and b⁴. By this construction and arrangement of the matrix the latter is highest at the portion b⁴, is next highest at the portion b³, is still lower at b²; and is lowest at the base sheet 105 where the cut out portions are provided. The small portions b' are pasted on the sheet on the same level as the large portion b², as light impressions similar to those produced by b² are required at these points. Of 110 course there may be as many thicknesses of superposed pieces as may be desired, according to the graduation of the impressions to be obtained; and these superposed portions may consist of smaller pieces than 115 those shown and they may be distributed or placed at the various parts of the proof in accordance with the character of impressions to be taken from the printing plate. After the formation of the matrix thus in accordance with the tones of the subject it is laid upon the flat bed of a shaving machine with the built-up portions uppermost, and the plate to be affected thereby is then laid face down on said matrix and in proper register 120 therewith. The back of the plate is now to be subjected to the action of a shaving knife for the purpose of producing in or on the back of the plate a series of 125 depressions and elevations the reverse of those 130

formed in the matrix by the built-up and cut-out portions of the latter, in order that the said depressions and elevations thus formed in the back of the plate may subsequently be produced or formed in the face of the plate by a succeeding step in the treating process, as will hereinafter appear.

The plate and matrix having been properly placed on the bed of the shaving machine, as illustrated at Fig. 4, the shaving knife, which is mounted to run true in a given plane across the back of the plate, is set so as to cut a thin shaving or chip from the back of the plate, and the knife is then started on its travel to cut a shaving or chip which will include all portions of the plate that are supported by the built-up portions of the matrix beneath. The knife, however, will not cut from the back of the plate those portions of the plate which are unsupported by the matrix; that is to say, the pressure of the knife upon the back of the plate is such that when the lines or points of pressure of the knife on the plate reach a place or places opposite to or in alignment with depressions or cut-outs in the matrix, such portion or portions of the plate will, under the pressure of the knife, be deflected or depressed to either fill or partially fill such depressions or cut-aways in the matrix, and the knife being unable to follow the deflection or depression of the plate will in consequence pass over such place or places on the back of the plate without shaving or cutting the same, and thus at the end of the first cut or chip there will be produced in the back of the plate depressed and elevated portions; that is to say, the plate will be of different thicknesses, being thinner where the cuts were taken and of the normal thickness where the metal escaped the knife. It may be necessary to take several such cuts from the back of the plate so as to produce finally elevations of sufficient height and depressions of sufficient depth subsequently to produce elevations of sufficient height and depressions of sufficient depth for the purpose of obtaining respectively the desired heavy and light printing from the face of the plate. Depending upon the character or construction of the shaving machine either the knife or the bed of the machine will be adjusted for the succeeding cuts, or if neither of these members be adjustable, as in some shaving machines, there will be added underneath the matrix succeeding sheets of thin paper to raise the back of the plate to the cutting plane of the knife. When the next cut is taken the plate will again be deflected or depressed into the hollows or cut-aways in the matrix by the pressure of the knife when it arrives opposite such portions in the manner hereinbefore explained, and at the completion of this cut it will be noted that the elevations on the back of the plate are greater than before and

that the depressions thereon are likewise deeper. In taking the first cut we may assume that the knife is set to shave a thickness equal to the uppermost ply or piece b^4 .

As long as the plate is supported by the matrix by the part b^4 and its underlying pieces, the knife will take off an even thickness of shaving, but when the knife arrives over the first step or at the inner edge of the portion b^4 , the crowding action of the knife will press the metal downwardly until the face of the plate opposite the parts b^3 takes a bearing on, or is stopped by, the portion b^3 and its underlying portions, and the knife will fail to cut the upper portion of the plate at such depressed portion, and similarly as the knife continues its passage it will deflect or press down those portions of the plate that are opposite the stepped or lowered portions of the matrix; and therefore at the completion of the cut it will be found that only those portions of the back of the plate have been cut which were supported by the up-built portions b^4 of the underlying matrix and hence there will be, on the back surface of the plate, a series of depressions corresponding in number to the high spots or pieces b^4 on the matrix. When the next cut is made the knife will plough along until it meets the first elevation or set of elevations on the back of the plate or until it again comes opposite the stepped portions of the matrix, when it will depress the plate until the face thereof takes a bearing on the portions b^3 or the second step down on the matrix; but, inasmuch as there is a projection or a series of projections on the plate at such place or places which extend above the plane of the cutting edge of the knife, the knife will then take a shaving not only off the parts of the plate over the places b^4 but also off the parts over the pieces b^3 ; but when the knife arrives at the depressions b^4 , it will depress the plate thereinto, and since at this locality there is not enough projection of the metal on the back of the plate to extend above the cutting plane of the knife, the knife will fail to take off the metal at this place during its travel at this time. On the next run of the knife, however, when the plate is pressed down on to the seat b^2 , there will be a portion of the back of the plate which extends above the cutting plane of the knife and hence such extended portion together with portions over b^4 and b^3 will be cut off by the knife on said next trip. In this way the knife keeps taking off more and more of a shaving from the back of the plate as the face of the plate is pressed deeper and deeper into the matrix or until the plate finally takes a support on all the steps and on the bed of the shaving machine at the cut-out portions of the matrix, and so that the last chip or shaving taken from the plate will be a substantially whole or unbroken

one; that is to say, one without any interior openings, breaks or spaces. It may be said here that the shape of the first chip corresponds substantially to the outline of the 5 uppermost seat or piece b^4 , the second chip to that of the seat or piece b^3 , and so on down to the lowest; but owing to the crowding and pressing action of the knife on the 10 particles of metal constituting the chip or shaving, the latter is compressed or condensed to such an extent that when the cutting operation is completed, the chip may be of only half the length of the plate.

It should be borne in mind that owing to 15 the copper shell on the face of the electro-type plate, the plate has a certain amount of resiliency, and hence that when the various 20 portions of the plate are deflected or pressed down by the pressure of the passing knife, such deflections are but temporary and that 25 as soon as the pressure of the knife is removed, such deflected portions spring back to normal position. Therefore it will be seen that when all of the several shaving operations are concluded, the face of the plate 30 will be straight and even, but the back of the plate will be uneven or irregular and consist of depressions and elevations the reverse of those in the matrix, and it will be understood 35 that such depressions and elevations in the back of the plate are those formed by the cutting process and as predetermined and controlled by the make-up or construction of the matrix.

After the shaving operation just described 40 and while the matrix is still in register with the plate the latter is subjected to the action of heat and pressure and the projections on the back of the plate are forced forward and similar projections forced into the hollows or depressions in the matrix at the face of the plate, and at the same time the back of the plate is pressed true or even as represented at Fig. 7. After this operation, as 45 before described, the plate and matrix are removed from the heating and pressing machine and placed in another press where there is no heat and which is preferably kept cool, and by means of pressure the face of the 50 plate is positively and finally set to conform to the outlines of the matrix, and when removed from the last mentioned press the plate will have the appearance represented at Fig. 8, wherein it will be observed that the 55 back of the plate P' is true or even while the face P^2 , which constitutes the printing surface of the plate, is irregular or high and low at different places so as to have a varying pressure on the paper in the printing operation, and thus yield varying strengths of 60 impression or heavy and light impressions on the surface of the paper and at the places predetermined by the making of the matrix from a proof or copy of the matter or subject which the plate is to bear.

Of course my improved plates may be printed from while they are in their flat state or they may be curved to go on a plate cylinder as usual. When the plates are to be curved they are curved with the matrix and 70 blotter under heat and pressure in a suitable press, and then cooled and set subsequently in a similar press.

It will be seen that by my invention I have produced a printing plate wherein there 75 are depressions and elevations in the printing face formed at those portions where the impressions are to be respectively light and dark; also that the printing plate or electro-type is made with an even back while its 80 face is formed or provided with undulating portions at predetermined places so as to yield different predetermined strengths of impression. It will also be seen that in carrying out my process I first prepare a preliminary graduated surface in accordance with the printing tones to be obtained and then operate on the plate by pressure through this preliminary or intervening graduated 85 surface to produce the desired graduated 90 printing surface in the face of the plate. Furthermore, it will be seen that I produce the graduations necessary for the printing surface of the plate by applying graduated pressures or different degrees of pressure to 95 various sections of the printing plate. My process as herein described also results in reducing the thickness of the plate in accordance with some of the tones of the subject and in the fixing permanently in the face of 100 the plate of gradations in accordance with such tones.

It will be seen that in practicing my process I produce a printing plate having graduated elevations on its printing surface corresponding in order with the solid or dark tones and the intermediate tones of the subject on the face of the plate. It will also be seen that I have produced a printing plate varying in structural thickness in accordance with the several pressures required for printing and in accordance with the various tones of the subject on the face of the plate. Such a printing plate has the sections which are designed to print the darker shades permanently elevated above the levels of the sections adapted for the lighter shades, and the levels are graded one into the other from the permanently elevated parts to the 110 lightest printing shades, so that in profile the plate is uneven or irregular in its printing face. In short it will be observed that I have produced a printing plate wherein the required "make-ready" is permanently produced in the face of the plate.

So far as my knowledge extends, no printing plate of this description has ever before been produced, and in consequence of my improvements in the plate it will be seen that all the objectionable, expensive and difficult 120 125 130

work of "making ready" may now be entirely dispensed with, although I may add here that if after the making of the plate the pressman should at any time during the course 5 of the printing therefrom desire to change the character of impressions by further lightening or increasing the same he may for such purpose "underlay" or "overlay" in the usual manner, but ordinarily the plates may 10 be made at the outset to conform exactly to what is required by the pressman or to what is demanded by the nature of the plate to be worked from.

In so far as certain features of my improvements in the art of treating or manipulating the plate are concerned, it will be understood that I do not wish to be limited to each and all of the steps of the complete process to which I prefer to subject the plate, for some 15 of such steps may be used without others or in connection with still other steps or modes of treatment to produce certain of the results produced by me and to avoid either in whole or in part the work of "underlaying" and 20 "overlaying." I desire to cover herein not only the process as an entirety, but also the essential steps or sub-processes thereof.

The following are some of the advantages to be obtained with plates produced by this 25 process: The pressman can prepare the plates ahead. When he receives an order to put them on the press, they are ready and no further work on them is required. One matrix can be used for any number of duplicate plates;—a great advantage. The usual underlays and overlays are not required, since their effects are produced on the face of the plates and the "strike-off" between the 30 cut overlay and plate which happens so often is obviated, resulting in saving a vast amount of valuable time. The plates being level they do not rock or spring and owing to their stability on the block the usual wear is prevented. In case of long runs the quality of 35 the work is kept up to a pleasing standard. Saves renewing electro-plates and unnecessary electro-plate bills. The press is not standing idle for hours while the pressman is preparing underlays and overlays. The 40 press can be immediately started up as soon as the plates are properly imposed and registered. The original uneven thickness always found in electro-plates (caused by the electro-type process) is entirely gotten rid of, 45 as the preparation of plates by the foregoing method removes all such imperfections, saving a vast amount of work and expense. Vignetted cuts are always a bane to the pressman and require excellent and careful 50 judgment in making ready; also constant watching when the press is producing work. Such plates on account of their light printing character always get thick or wear out either by over-make-ready or instability on 55 the block.

Plates treated by the foregoing process are absolutely perfect, as without any injury whatever its hard edges are slightly depressed, obtaining a light and delicate impression without the usual delicate treatment 60 on the cylinders or the use of engraving tools, roulettes or knocking below the printing pressure with a punch and hammer.

What I claim as my invention is:

1. That improvement in the art of treating manufactured relief printing plates which 75 consists in mechanically producing in the printing face of such plate depressions and elevations at predetermined places where the printing is to be respectively light and heavy, 80 and in also evening or leveling the back of the plate.

2. That improvement in the art of treating manufactured relief printing plates which 85 consists in preparing from a proof of the matter which is on the face of the plate to be printed from a matrix with high and low portions corresponding respectively to the depressions and elevations which are to appear in the face of the printing plate, then placing 90 the matrix and the printing plate face to face and subjecting the two to pressure, and in then evening or leveling the back of the plate.

3. That improvement in the art of treating manufactured relief printing plates which 95 consists in preparing from a proof a matrix with high and low portions corresponding respectively to the depressions and elevations which are to appear in the printing plate, then placing the matrix and the printing 100 plate face to face subjecting the two to heat and pressure, and in evening or leveling the back of the plate.

4. That improvement in the art of treating manufactured relief printing plates which 105 consists in taking a copy of the face of the plate to be printed from, in preparing from such copy a matrix with high and low portions and then forcing the face of the printing plate against the matrix and producing in 110 the plate depressions and elevations the reverse of those in the matrix, and in subsequently evening or leveling the back of the plate.

5. That improvement in the art of treating 115 manufactured relief printing plates which consists in forming on a proof sheet a matrix with an uneven surface and then pressing said matrix and plate together and producing in the latter an uneven printing surface 120 corresponding in reverse to that of the matrix.

6. That improvement in the art of treating manufactured relief printing plates which 125 consists in forming on a proof sheet a matrix with an uneven surface the reverse of that to be produced in the plate and then by means of heat and pressure causing the printing face of the plate to conform to the inequalities of the matrix.

7. That improvement in the art of treating 130

manufactured relief printing plates which consists in taking an impression of the matter on the face of the plate to be printed from and determining from said impression where the face of the printing plate is to be changed; then preparing a matrix with high and low portions corresponding respectively with the depressions and elevations which are to be produced in the plate, and then applying such matrix to the face of the plate and producing in the latter the said predetermined depressions and elevations.

8. That improvement in the art of treating manufactured relief printing plates which consists in taking a proof of the plate, forming a matrix therefrom, producing from said matrix projections or elevations in the back of the plate by a cutting operation, and then transferring same to the face of the plate.

9. That improvement in the art of treating manufactured relief printing plates so as to obtain portions thereof which shall print heavier than other portions of the plate, which consists in preparing a matrix from a suitable sheet of fabric by cutting out therefrom portions corresponding to those portions of the plate which are to produce the heavier impressions, then applying said matrix to the face of said plate with the cut out portions in register with said portions of the plate which are to print heavier, and then subjecting the matrix and plate to pressure and causing the portions of the plate registering with the cut out portions of the matrix to be elevated above the remaining portions of the plate.

10. That improvement in the art of treating manufactured relief printing plates so as to obtain portions thereof which shall print heavier than other portions of the plate, which consists in preparing a matrix from a suitable sheet of fabric by cutting out therefrom portions corresponding to those portions of the plate which are to produce the heavier impressions, then applying said matrix to the face of the said plate with the cut out portions in register with said portions of the plate which are to print heavier, and then subjecting the matrix and plate to heat and pressure and causing the portions of the plate registering with the cut out portions of the matrix to be elevated above the remaining portions of the plate.

11. That improvement in the art of treating manufactured relief printing plates so as to obtain portions thereof which shall print lighter than other portions of the plate, which consists in preparing a matrix from a suitable sheet of fabric by building up thereupon portions corresponding to those portions of the plate which are to produce the lighter impressions, then applying said matrix to the face of said plate with the built up portions in register with the said portions of the plate which are to print lighter, and then subject-

ing the matrix and plate to pressure and causing the portions of the plate registering with the built up portions of the matrix to be depressed below the remaining portions of the face of the plate.

12. That improvement in the art of treating manufactured relief printing plates so as to obtain portions thereof which shall print lighter than other portions of the plate, which consists in preparing a matrix from a suitable sheet of fabric by building up thereupon portions corresponding to those portions of the plate which are to produce the lighter impressions, then applying said matrix to the face of said plate with the built up portions in register with the said portions of the plate which are to print lighter, and then subjecting the matrix and plate to heat and pressure and causing the portions of the plate registering with the built up portions of the matrix to be depressed below the remaining portions of the plate.

13. That improvement in the art of treating manufactured relief printing plates so as to obtain portions thereof which shall print light and other portions which shall print heavier, and which consists in preparing a matrix from a suitable sheet of fabric by building up portions of the sheet for those portions of the plate which are to print light and cutting out portions of the sheet for those portions of the plate which are to print heavier, and then subjecting the matrix and plate to pressure and causing the portions of the plate registering with the built up portions of the matrix to be depressed and those portions of the plate registering with the cut out portions of the matrix to be elevated.

14. That improvement in the art of treating manufactured relief printing plates so as to obtain portions thereof which shall print light and other portions which shall print heavier, and which consists in preparing a matrix from a suitable sheet of fabric by building up portions of the sheet for those portions of the plate which are to print light and cutting out portions of the sheet for those portions of the plate which are to print heavier, and then subjecting the matrix and plate to heat and pressure and causing the portions of the plate registering with the built up portions of the matrix to be depressed and those portions of the plate registering with the cut out portions of the matrix to be elevated.

15. That improvement in the art of preparing printing plates which consists in producing in the back of the plate depressions and elevations at predetermined places, and then subsequently producing similar depressions and elevations in the face of the plate where the printing is to be respectively light and heavy by pressing forward the elevations produced in the back of the plate.

16. That improvement in the art of pre-

- paring printing plates which consists in producing in the back of the plate depressions and elevations at predetermined places and then subsequently by heat and pressure producing similar depressions and elevations in the face of the plate where the printing is to be respectively light and heavy by pressing forward the elevations produced in the back of the plate.
16. 17. That improvement in the art of preparing printing plates which consists in preparing a matrix with high and low portions corresponding respectively to the depressions and elevations which are to appear in the face of the printing plate, then placing the matrix and printing plate face to face, and then subjecting the same to pressure and to the action of a shaving knife and producing thereby in the back of the plate depressions and elevations the reverse of those in the matrix.
18. That improvement in the art of preparing printing plates which consists in placing against the face of the printing plate the face of a matrix having high and low portions corresponding respectively to the depressions and elevations which are to appear in the printing plate, then subjecting the back of the plate to a plurality of shaving operations and producing thereby a series of depressions and elevations on the back of the plate, and then subjecting the plate and matrix to the action of heat and pressure and causing the depressions and elevations to appear in the face of the plate and the back of the plate to become smooth and even.
19. That improvement in the art of preparing printing plates which consists in placing face to face a plate and a prepared matrix, then shaving the back of the plate and producing thereon high and low portions the reverse of those in the matrix, and then subjecting the plate and matrix to the action of heat and pressure and causing depressions and elevations to appear in the face of the plate corresponding to those which had previously been formed in the back of the plate.
20. That improvement in the art of preparing printing plates so as to obtain an uneven printing face, which consists in applying to the face of the plate when cold a previously prepared uneven faced matrix, then subjecting the plate while under pressure to the action of a shaving knife and producing thereby on the back of the plate a series of depressions and elevations, and then subjecting the plate to heat and pressure while still in register with the matrix and causing substantially corresponding depressions and elevations to appear in the face of the plate and the back of the plate to become smooth and even.
21. That improvement in the art of preparing printing plates which consists in first producing in the back of the plate a series of depressions and elevations and in then forcing the metal toward the face of the plate to produce therein a series of substantially similar depressions and elevations.
22. That improvement in the art of preparing printing plates which consists in first producing a series of depressions and elevations and in then forcing the metal from the back of the plate toward the face of the plate to produce therein a series of substantially similar depressions and elevations.
23. That improvement in the art of preparing printing plates which consists in first producing in the back of the plate a series of depressions and elevations and in then forcing the metal toward the face of the plate to produce therein a series of substantially similar depressions and elevations and simultaneously smoothing or evening the back of the plate.
24. That improvement in the art of preparing printing plates which consists in producing in the back of the plate a series of depressions and elevations by a series of shaving operations, and in subsequently producing in the face of the plate by pressure a series of substantially similar depressions and elevations by forcing the elevations forward toward the face of the plate.
25. That improvement in the art of preparing printing plates which consists in applying to the face of the plate a suitable matrix, and then by a series of shaving operations under pressure producing in the back of the plate irregularities corresponding to those in the matrix, and in then by heat and pressure transferring such irregularities from the back of the plate to the face of the plate and causing the back of the plate to become substantially smooth and even.
26. That improvement in the art of preparing printing plates which consists in preparing the back of the plate with depressions and elevations corresponding to those which are to appear in the face of the plate, and in then subjecting the plate to pressure and causing said depressions and elevations to appear in the face of the plate.
27. That improvement in the art of preparing printing plates which consists in preparing the back of the plate with depressions and elevations corresponding to those which are to appear in the face of the plate, and in then subjecting the plate to heat and pressure and causing said depressions and elevations to appear in the face of the plate.
28. That improvement in the art of preparing printing plates which consists in producing in the back of the plate an uneven surface, then applying to the face of the plate a matrix having a corresponding uneven surface, and then subjecting the two to pressure.
29. That improvement in the art of preparing printing plates which consists in pro-

ducing in the back of the plate an uneven surface, then applying to the face of the plate a matrix having a corresponding uneven surface, and then subjecting the two to heat and pressure.

30. That improvement in the art of preparing printing plates which consists in producing an unevenness in the back of the plate by cutting operations and while the face of the plate is held against a correspondingly uneven faced matrix.

31. That improvement in the art of preparing printing plates which consists in producing an unevenness in the back of the plate by cutting operations and while the face of the plate is held against a correspondingly uneven faced matrix, and then subjecting the plate and matrix to the action of heat and pressure and causing the unevenness in the back of the plate to appear in the face of the plate and the back of the plate to become substantially smooth and even.

32. That improvement in the art of preparing printing plates which consists in producing in the back of the plate a series of depressions and elevations by a series of shaving operations and controlling the production of such depressions and elevations by an uneven faced matrix applied to the face of the plate.

33. That improvement in the art of preparing printing plates which consists in producing in the back of the plate a series of depressions and elevations, then applying to the face of the plate any suitable soft material such as blotting paper, and applying to the outer side of such material a matrix having a face corresponding substantially to the depressions and elevations in the back of the plate, and then subjecting the whole to heat and pressure.

34. That improvement in the art of preparing printing plates which consists in producing in the back of the plate a series of depressions and elevations, then subjecting said plate to heat and pressure together with a matrix applied to the face of the plate and having depressions and elevations corresponding substantially to those on the back of the plate, and then subjecting the plate and matrix to the action of cold and pressure.

35. The process herein described, of treating a printing plate for the purpose of giving greater prominence to the different parts of its face, according to the heavier or lighter imprint desired, consisting in first obtaining an impression of the plate on a sheet of suitable fabric, then forming a matrix by cutting out certain portions of said sheet and building up other portions with additional thickness of fabric, and afterward placing said matrix and the plate face to face, and subjecting them together to heat and pressure, substantially as herein set forth.

36. The process herein described, of treating printing plates by first obtaining an impression of the plate on a sheet of suitable fabric; second, forming a matrix by cutting out certain portions of said sheet and building up other portions with one or more additional thicknesses of fabric; third, placing said matrix and plate face to face while shaving the back of the plate; and fourth, subjecting to heat and pressure the said shaved plate and the matrix while facing each other with an interposed sheet of soft material, substantially as herein set forth. 70 75

37. The process herein described of treating a printing plate by first obtaining on a sheet of suitable fabric an impression from an ordinary electrotype plate; second, forming a matrix by cutting out from said sheet those portions corresponding with the parts of the plate from which the blacker or heavier imprint is desired and building up those portions corresponding with the parts of the plate from which lighter imprints are desired by the superposition and securing thereon of additional thickness of paper of the requisite form; third, placing this matrix and the plate face to face and shaving the back of the plate to reduce its thickness where desired; fourth, placing said matrix on a board with a sheet of soft paper over the matrix and laying the plate on the soft sheet with its face thereon; fifth, subjecting said board, matrix, soft sheet and plate together to pressure and heat, and finally, subjecting said board, matrix, soft sheet and plate to simultaneous pressing and cooling operations, substantially as herein set forth. 80 85 90 95 100

38. That improvement in the art of preparing printing plates which consists in producing by pressure the graduations necessary for the printing surface of the plate. 105

39. That improvement in the art of preparing printing plates which consists in applying graduated pressures to the printing plate to form graduations in the face of the plate. 110

40. The process of producing a graduated printing surface which consists in first producing a graduated surface representing the printing tones and then by pressure producing therefrom a graded surface in the face of the plate. 115

41. That improvement in the art of preparing printing plates which consists in first preparing a preliminary graduated surface and then by pressure causing graduations predetermined by the preliminary graduated surface to appear in the face of the plate. 120

42. That improvement in the art of preparing printing plates which consists in applying pressure to the plate through an intervening graduated surface to form graduations in the face of the plate. 125

43. That improvement in the art of preparing printing plates which consists in forc- 130

ing into the face of the plate relative elevations and depressions corresponding to the tones of the subject.

44. The process of producing a graduated printing surface which consists first in preparing a graduated surface in accordance with the printing tones to be obtained and then operating on the plate with said graduated surface so as to cause said graduated surface to produce the desired graduated printing surface in the face of the plate.

45. The process of producing a graduated printing surface which consists first in preparing a graduated surface and then by pressure causing the graduations of said graduated surface to be permanently fixed in the face of the printing plate.

46. That improvement in the art of preparing printing plates which consists in reducing the thickness of the plate in accordance with some of the tones of the subject and applying pressure to produce gradations in the face of the plate in accordance with the tones of the subject.

47. That improvement in the art of preparing printing plates having "make-ready" formed therein which consists in applying a matrix to the plate and subjecting the plate and matrix to heat and pressure.

48. The herein described process of producing printing surfaces which consists in first forming a relief printing surface in a thin plate, and then applying different degrees of pressure to various sections thereof, thereby producing permanent differences in profile in said plate, the levels of which are in correspondence with the darkness of the shades to be printed by the sections.

49. The herein described process of producing printing surfaces which consists in first forming a graduated surface and then through said surface applying different degrees of pressure to various sections of the printing plate, thereby producing permanent differences in profile in said plate, the levels of which are in correspondence with the shades or tones to be printed by the sections.

50. The herein described process of producing printing surfaces, which consists first in forming a relief printing surface in a yielding material and then producing a graded printing surface by applying different degrees of pressure to various sections thereof and so as to produce permanent graded alterations in the surface in profile.

51. That improvement in the art of treating manufactured relief printing plates which consists in producing in the printing face of the plate depressions and elevations at predetermined places where the printing is to be respectively light and heavy and in also evening or leveling the back of the plate and in then subsequently curving the plate.

52. That improvement in the art of treating manufactured relief printing plates which

consists in forming on a proof sheet a matrix with an uneven surface, then pressing said matrix and plate together and producing in the latter an uneven printing surface corresponding in reverse to that of the matrix, and in then curving said plate with the matrix applied to the face side thereof.

53. That improvement in the art of treating manufactured relief printing plates which consists in forming on a proof sheet a matrix with an uneven surface, then pressing said matrix and plate together and producing in the latter an uneven printing surface corresponding in reverse to that of the matrix, and in then curving said plate under heat and pressure with a matrix applied to the face side of the plate and a soft backing interposed between the matrix and the plate.

54. That improvement in the art of treating manufactured relief printing plates which consists in forming on a proof sheet a matrix with an uneven surface, then pressing said matrix and plate together and producing in the latter an uneven printing surface corresponding in reverse to that of the matrix, in then curving said plate under heat and pressure and with a matrix applied to the face side thereof, and in then subsequently cooling and setting said plate under pressure.

55. That improvement in the art of preparing printing plates which consists in preparing a matrix and in producing in the back of the plate depressions and elevations at predetermined places where the printing is to be respectively light and heavy, in then subsequently producing similar depressions and elevations in the face of the plate, and in then curving the plate with a matrix applied to the face side thereof.

56. That improvement in the art of preparing printing plates which consists in preparing a matrix and in producing in the back of the plate depressions and elevations at predetermined places where the printing is to be respectively light and heavy, in then subsequently producing similar depressions and elevations in the face of the plate, in then curving the plate under heat and pressure with a matrix applied to the face side of the plate, and in subsequently cooling and setting the plate under pressure.

57. That improvement in the art of preparing printing plates which consists in applying a prepared matrix to the face of the plate, then shaving the back of the plate and producing therein high and low portions the reverse of those in the matrix, in then subjecting the plate and matrix to the action of heat and pressure and causing depressions and elevations to appear in the face of the plate corresponding to those which had previously been formed in the back of the plate, and in then curving the plate under heat and pressure with a matrix applied to the face side of the plate.

58. That improvement in the art of preparing printing plates which consists in applying a prepared matrix to the face of the plate, then shaving the back of the plate and producing therein high and low portions the reverse of those in the matrix, in then subjecting the plate and matrix to the action of heat and pressure and causing depressions and elevations to appear in the face of the plate corresponding to those which had previously been formed in the back of the plate, in then curving the plate under heat and pressure with a matrix applied to the face side of the plate, and in then cooling and setting the plate under pressure.

59. That improvement in the art of preparing curved printing plates having "make ready" formed therein, which consists in curving the plate with a matrix or relief form applied to the face side of the plate.

60. That improvement in the art of preparing curved printing plates having "make ready" formed therein, which consists in curving the plate under heat and pressure with a matrix or relief form applied to the face side of the plate.

61. That improvement in the art of preparing curved printing plates having "make ready" formed therein, which consists in curving the plate under heat and pressure with a matrix applied to the face side thereof and soft material interposed between the matrix and the plate.

62. That improvement in the art of preparing curved printing plates having "make ready" formed therein, which consists in curving the plate under heat and pressure with a matrix applied to the face side of the plate, and in then subsequently cooling and setting the plate under pressure.

63. That improvement in the art of preparing curved printing plates having "make ready" formed therein, which consists in curving the plate under heat and pressure and with an applied matrix.

64. As a new article of manufacture, a relief printing plate whose face constitutes the printing surface and is formed with depressions and elevations at those portions where the impressions are to be respectively light and dark and whose back is even and level.

65. As a new article of manufacture, a relief printing plate having an even and level back and a predetermined undulating face which constitutes the printing surface of the plate and which is adapted to yield different predetermined heavy and light impressions, heavy impressions at the raised portions of the plate and light impressions at the depressed portions of the plate.

66. As a new article of manufacture, a relief printing plate having an evenly pressed back and a pressed up printing face composed of a series of printing projections and depressions formed at predetermined places

where the printing pressures are to be respectively heavy and light.

67. A printing surface having the sections thereof, which are designed to print the darker shades, permanently elevated above the levels of the sections adapted for the lighter shades.

68. A printing surface having the sections thereof, which are designed to print the darker shades, permanently elevated above the levels of the sections adapted for the lighter shades, these levels being graded one into the other.

69. A printing block having an uneven printing face or surface, parts of said printing surface being raised to correspond to the darkly shaded parts of the subject to be printed, and other parts of its printing surface being depressed to correspond to the lighter shaded parts of the subject to be printed, the whole surface level of the block being a graduated printing surface.

70. A printing plate reduced in thickness from the back and depressed from the front to correspond to the successive gradations of light and shade represented by the picture on the face.

71. A printing surface having sections thereof which are designed to print the darker shades permanently elevated above the levels of the sections adapted for the lighter shades, the levels being graded one into the other from the permanently elevated parts to the lightest printing shade.

72. As a new article of manufacture, a relief printing plate having a permanently formed graduated printing surface.

73. As a new article of manufacture, a printing plate varying in structural thickness in accordance with the several pressures required for printing the different tones.

74. As a new article of manufacture, a printing plate varying in structural thickness in accordance with the several pressures required for printing the different tones, the back of the plate being even.

75. As a new article of manufacture, a graduated relief printing plate varying in thickness in accordance with the various tones of the subject on the face of the plate.

76. As a new article of manufacture, a graduated relief printing plate varying in thickness according to the various tones of the subject on the face of the plate, and even on the back.

77. As a new article of manufacture, a printing plate having graduated elevations on its printing surface corresponding with the dark tones and the intermediate tones of the subject on the face of the plate the dark tones being the highest.

78. As a new article of manufacture, a printing plate having the required "make-ready" permanently produced in the face of the plate.

79. As a new article of manufacture a relief printing plate having a predetermined uneven permanently formed printing face which is adapted to yield different predetermined heavy and light impressions.

80. As a new article of manufacture, a curved relief printing plate having an even back and a predetermined uneven printing face which is adapted to yield different predetermined heavy and light impressions.

81. As a new article of manufacture, a curved relief printing plate having a permanently formed graduated printing surface.

82. As a new article of manufacture, a curved printing plate having the required "make-ready" permanently produced in the face of the plate.

In testimony, that I claim the foregoing as my invention, I have signed my name in presence of two witnesses, this 19th day of 20 December 1901.

MILTON ABBOTT MCKEE.
